(No Model.)

D. J. POWERS.

UPRIGHT OR FOLDING BED.

No. 398,747.

Patented Feb. 26, 1889.

UNITED STATES PATENT OFFICE.

DAVID J. POWERS, OF CHICAGO, ILLINOIS, ASSIGNOR TO THE UNION WIRE MATTRESS COMPANY, OF ILLINOIS.

UPRIGHT OR FOLDING BED.

SPECIFICATION forming part of Letters Patent No. 398,747, dated February 26, 1889.

Application filed July 8, 1887. Serial No. 243,745. (No model.)

To all whom it may concern:

Be it known that I, DAVID J. POWERS, a citizen of the United States, residing at Chicago, in the county of Cook and State of Illinois, 5 have invented certain new and useful Improvements in Upright or Folding Beds, which I desire to protect by Letters Patent of the United States, and of which the following is a specification.

10 My improvement consists in certain devices for connecting the stationary and unfolding portions of this class of beds.

Figure 1 of the drawings shows the bed unfolded ready for use. Fig. 2 shows it folded up. Fig. 3 is a back view of the bed. Fig. 4 is a top view of back, with sections of the stationary portion A, showing vertical grooves and the rollers that guide the back up and down. Fig. 5 also shows the same enlarged.

20 Fig. 6 shows a roller-guide enlarged, the same also being seen applied in Figs. 1 and 2. Fig. 7 shows the detachable back.

Like letters and figures indicate like parts both in the drawings and specification.

25 The stationary portion A and folding and unfolding portion B of the bed are made in any usual form and manner; but in connecting the two sections together I employ supporting-arms b b, pivoted to the outer side of unfolding section B at their top ends and resting in pockets a a near the base and inner side of the stationary section A, as shown in Figs. 1 and 2 in both their folded and unfolded positions.

35 To the rear end of section B is hinged the sliding back K, adapted to move freely up and down, being guided by rollers L in grooves M of section A at its top portion, and by its connection with the head end of section B, and so 40 adapted that it can freely follow the said section B from its position as seen in Fig. 1 to the position shown in Fig. 2. Back K carries the counterbalancing-weights N, and is pivoted to the head of section B, with slip-hinges

45 O, (shown in Fig. 7,) which, when the bed is unfolded, enables the back to be lifted up, and supported by hooks P, engaged upon pins Q upon section A, thus separating the back K from section B, after which section B can be 50 readily removed from section A by raising rollers V above the guide-cams X, the arms b

being merely secured in pockets that enable them to be readily withdrawn with section B. Thus sections A and B can be readily connected and disconnected, as found desirable, 55 in moving, cleaning, &c., without the use of tools—an important desideratum in such heavy structures.

It is desirable and a preferable construction, as affording easier action, that the swinging 60 or movable part of the bed be so pivotally connected with the stationary section that the restraint which prevents the former from separating or falling forward from the latter in the direction of its length when extended shall 65 depend upon anti-friction against guides or cams. To the end above named I employ arms b b, that are freely supported in pockets near the lower part of the stationary portion and within its dimensions. The upper ends of 70 these arms are attached to the folding part of the bed pivotally and with such relation thereto that when said folding part is down they serve as braces with an outward inclination. Then as a guide and to retain the movable 75 section B in position during the operation of folding or unfolding, I provide cam-plates X, having rear curved faces or sides. On the rails of section B are provided rollers V, adapted to engage with the rear face of cam- 80 plates X and travel against the latter in the folding or unfolding movements. The cams X are provided at the top and bottom with depressions or ogee curves, into the upper of which the rollers seat themselves when section 85 B is down, and when the latter is up the rollers are seated in the lower curves. This operates to partially secure section B in either position, and yet is not so rigid but what a little force exerted at either point will disengage it, 90 thus making a very simple and convenient locking device for such a bed.

I do not design to limit my invention to the use of a sliding weighted back, as the weights can also be applied directly to the inner ends 95 of the unfolding section of the bed and work practically well, although I prefer the sliding weighted back, as shown.

Having thus described my invention, what I claim as new, and desire to secure by Letters 100 Patent, is—

1. In a folding bed, curved cams or plates

vertically placed and facing to the rear on the stationary section of the bed, rollers attached to the sides of and near the inner end of the movable section adapted to engage with and travel against the rear faces of the cams, and arms that are pivoted to the folded section of the bed as a support for the latter, which are movably supported at or near the lower portion of the stationary section, so that when the bed is unfolded said arms incline outwardly and when the bed is folded their position is vertical, or approximately so.

2. In a folding bed, a movable section and

a stationary section in which the movable section is supported on pivotal arms near the head thereof, and is provided with rollers or wheels, in combination with cams fixed to the stationary section, said cams having, respectively, an upper and lower seat or ogee curve adapted for partial retention of said wheels in either the raised or lowered position of the movable section, substantially as set forth.

DAVID J. POWERS.
